CARBURETOR

Anthony J. Metz, Davenport, Iowa, assignor of
one-half to J. R. Porter, Davenport, Iowa

Application March 23, 1933, Serial No. 662,267

11 Claims. (Cl. 261—72)

The present invention pertains to improvements in carburetors and more particularly to the securing of greater efficiency in the operation thereof. Among the objects of this invention are to provide a carburetor which is so constructed that a minimum amount of the gas issuing from the fuel nozzle will come in contact with the throttle valve and be condensed thereby into liquid form; to provide an improved carburetor which is so constructed that just enough gasoline will be provided when the engine is idling to take care of the gas needed for this purpose, the same being capable of supplying, as needed, all the fuel requisite for higher speeds; to provide an improved carburetor in which the air and gasoline required for idling speed of the engine will be injected into a venturi to be thoroughly co-mingled; to provide an improved carburetor in which substantially all of the fuel delivered for operation of the engine will be kept out of contact with the throttle valve; and such further objects, advantages, and capabilities as will hereafter appear and as are inherent in the construction disclosed herein. My invention further resides in the combination, construction, and arrangement of parts illustrated in the accompanying drawings and, while I have shown therein two different embodiments of this invention, I desire it understood that these are merely illustrative and are not to be interpreted in a limiting sense.

In the drawings annexed hereto and forming a part hereof.

Fig. 1 is a plan view of one form of my improved carburetor;

Fig. 2 is a vertical, substantially central section taken approximately along the plane indicated by the line 2—2, Fig. 1;

Fig. 3 is a transverse section taken substantially along the plane indicated by the line 3—3,

Fig. 1;

Fig. 4 is a transverse section taken substantially along the plane indicated by the line 4—4, Fig. 5;

Fig. 5 is a fragmentary vertical longitudinal section taken substantially along the plane indicated by the line 5—5, Fig. 4;

Fig. 6 is a plan view similar to Fig. 1 of another form of construction embodying my present invention;

Fig. 7 is a vertical longitudinal section of the structure shown in Fig. 6 and corresponding in general to the section shown in Fig. 2;

Fig. 8 is a vertical transverse section taken substantially along the plane indicated by the line 8—8, Fig. 6;

Fig. 9 is a transverse section taken in the plane of the line 9—9, Fig. 8.

Reference will now be made in greater detail to the annexed drawings for a more complete description of my invention as disclosed therein. The bowl 1 and float 2 may be of any conventional type. However, I provide on the cover 3 a species of boss 4 which is hollow as indicated at 5. This hollow space is connected at one side with the float chamber and at its opposite side with an air channel 6 which leads to an opening 7 at a point beyond the choke valve 8. This permits air to freely enter the channel 9 leading upwardly from the channel 6 to the air valve 10.

Suitable means 11, shown as a bolt having a frusto-conical point, is provided for adjusting the size of the opening at 10 for the regulation of the amount of air passing through the opening. Resilient means 12 is provided which is intended to hold the bolt 11 in adjusted position. A tube 13 is mounted in the bottom of the carburetor and has connection, as shown in Fig. 3, with the air valve passage 16, thus providing an adequate supply of air for the idling of the engine when the valve 14 is closed. As shown in Fig. 3, a screw-threaded plug 15 may be screwed into an opening in the side of the lower portion of the carburetor and may have a point which extends into an opening in the pipe 13 to properly position that pipe. Opposite this screw plug is an opening in the bottom portion of the pipe 13 which registers with the air valve 10 so that proper passage of air will always be assured. At its upper end, the pipe or tube 13 has a partially cylindrical head 16, as shown in Fig. 2. This has an opening 17 therethrough which communicates with the opening in the pipe and which directs the air and gasoline mixture into the venturi 18, located above the valve 14.

Spindles 19 and 20 support the valve plate 14 for partial rotation about the head 16, between the two positions shown in full and dotted lines in Fig. 2. Any suitable or usual throttle valve operating means may be connected to one of these spindles to actuate the valve into open or closed position.

An opening 21 leads from the float chamber and connects with the various fuel nozzles for supplying fuel for the operation of the motor. One of the tubes connected with this opening 21 is indicated by the numeral 22 and this ends just below the head 16 of pipe 13, through the center of which the pipe 22 extends. It will be seen from this that a supply of air passes upwardly through tube 13 around tube 22 and acts to draw

the fuel from the latter tube in the manner of an aspirator. This mixture of air and fuel passes outwardly through the opening 17 and is directed into the venturi 18 where the mixture is thoroughly co-mingled without contact of the fuel with any metal part after leaving the tube 22.

Other openings in the body of the carburetor, communicating with the opening 21, have tubes 23 and 24 mounted therein and serve to furnish additional fuel required for the running of the motor vehicle. Tube 23, being located more directly in the air current passing through the carburetor, is affected more strongly than the tube 24 and therefore begins sooner to supply fuel after the valve 14 is open. As the valve is open farther, the engine runs faster and creates a greater suction, causing a stronger air current to flow through the carburetor and fuel is then drawn through the tube 24 to supply the required additional fuel for the higher speeds. It will be seen from Fig. 2 that, when the valve 14 is opened, the fuel sprayed through the pipes 23 and 24 is not directed against any metal part but into the air current passing through the carburetor and this fuel is therefore not condensed into liquid form but is mixed in the venturi with the air passing therethrough.

The structure shown on Sheet 2 of the drawings differs from that shown on Sheet 1 in certain particulars due to the fact that this structure is designed for the use of a poppet valve type of throttle valve instead of the butterfly type. In this construction, a supporting tube 25 is rigidly mounted in the base of the carburetor and has slidably mounted therein a tube 26 provided externally with a flange 27 and having adjacent its upper end a valve head 28 which cooperates with the lower end portion of the Venturi tube 18. Surrounding the tubes 25 and 26 and pressing against the flange 27 and the bottom of the carburetor is a coiled spring 29 which serves to hold the valve closed, unless forcibly opened.

The upper end of the tube 26 is constricted, as shown at 30, to form a jet through which the air entering through valve 10 and the fuel entering through pipe 22 are injected into the venturi 18. It will be appreciated that when the valve 28 is closed, the suction of the engine will draw the air and fuel through these pipes in sufficient quantity to keep the engine idling. When it is desired to make the engine run faster, it is necessary to open the valve 28 and admit a greater supply of air and fuel and this opening of the valve is accomplished in the following manner.

The customary throttle valve opening means is connected to the shaft 19 which has a cam 31 projecting from one side thereof, as shown in Fig. 9. This cam engages a valve operating member 32 having a guide pin 33 upon its lower surface. Rotation of the shaft 19 therefore pushes member 32 downwardly, forcing pin 33 through the opening 34, as indicated in Fig. 8. Rising from member 32 is a part 35 which has a laterally extending fork 36 at its upper end, which fork straddles the pipe 26 and rests upon the flange 27. Therefore, when the cam 31 presses downwardly upon member 32, flange 27 and pipe 26 are caused to move downwardly with resulting compression of the spring 29. As the valve 28 is opened, air passing through the carburetor main air intake passes pipe 38 which communicates with the opening 21 from the float chamber and causes a suction on the fuel in this pipe. The result is that this fuel is aspirated

from the pipe and passes with the air between the valve 28 and venturi 18, the air and fuel being thoroughly intermingled in the venturi without the fuel coming, to any great extent, in contact with metal. This reduces the amount of condensation of the fuel to a minimum, thereby increasing the efficiency of the apparatus. When the shaft 19 is rotated in the opposite direction, the spring 29 causes closure of valve 28 and the air and fuel for keeping the engine running then pass through pipes 22 and 26, as heretofore described.

It will of course be understood that the specific description of structure set forth above may be departed from without departing from the spirit of this invention as set forth in this specification and the appended claims.

Having now described this invention, I claim:

1. A carburetor having a venturi, a throttle valve located below the venturi and in a position to admit air and fuel mixture to the venturi, a nozzle positioned below the venturi and so that when the valve is opened the fuel from the nozzle will not strike the valve and be condensed, a main air supply furnishing air to the carburetor, and a second nozzle located in the path of the air therethrough.

2. A carburetor comprising a venturi, a main air inlet, a throttle valve located between the air inlet and the venturi, an auxiliary air inlet leading through the throttle valve, a main fuel nozzle and an idling fuel nozzle delivering fuel into the auxiliary air intake between its two ends.

3. A carburetor comprising a venturi, a main air inlet, a throttle valve located between the air inlet and the venturi, an auxiliary air inlet leading through the throttle valve, and an idling fuel nozzle delivering fuel into the auxiliary air intake between its two ends, said carburetor having a fuel nozzle delivering fuel to the main air current below the throttle valve and in such a direction that the fuel leaving the nozzle will not be condensed by striking directly against metal.

4. A carburetor comprising a venturi, a main air inlet, a throttle valve located between the air inlet and the venturi, an auxiliary air inlet leading through the throttle valve, and an idling fuel nozzle delivering fuel into the auxiliary air intake between its two ends, the throttle valve being pivotally mounted about the delivery end of the auxiliary air inlet.

5. A carburetor comprising a venturi, a main air inlet, a throttle valve located between the air inlet and the venturi, an auxiliary air inlet leading through the throttle valve, and an idling fuel nozzle delivering fuel into the auxiliary air intake between its two ends, the throttle valve being slidably mounted and the fuel nozzle in the main air inlet being bent laterally to deliver the fuel above the throttle valve when the latter is opened.

6. A carburetor having a float chamber, a main air inlet, a venturi connected to the main air inlet, an auxiliary air inlet connecting the main air inlet with the upper portion of the float chamber, a series of fuel nozzles arranged in the main air stream below the venturi, and a fuel channel connecting the float chamber and the series of nozzles so that fuel may be sent from the float chamber to the nozzles in accordance with the opening or closing of the throttle valve and the suction of the engine upon the main air stream, the passage of the fuel from the nozzles to the venturi being entirely unobstructed when the throttle valve is open.

7. A structure as defined by claim 6 having

means for adjusting the effective opening of the auxiliary air inlet to vary the rate of speed of fuel for the idle running of the engine, the nozzle for furnishing the fuel for idle running of the engine being located substantially centrally of the main air stream.

5 8. In a carburetor having a venturi, a fuel nozzle having its delivery end below the most constricted part of the venturi, a tube, independent of the venturi, surrounding said nozzle in close proximity thereto to carry air around and beyond the nozzle before delivery of the fuel to the venturi, means to feed fuel to the nozzle and air to said tube, and a second fuel nozzle in the path 10 of the main air supply of the carburetor.

10 9. In a carburetor having a venturi, a fuel nozzle having its delivery end below the most constricted part of the venturi, a tube surrounding said nozzle in close proximity thereto to carry air around and beyond the nozzle before delivery 15 of the fuel to the venturi, a throttle valve surrounding the end portion of the air tube in such 20 relation thereto as to substantially prevent passage of air around the air tube when the valve 25 is closed, means to feed fuel to the nozzle and air

to said tube, and a second fuel nozzle in the path of the main air supply of the carburetor.

10 10. In a carburetor having a venturi, a fuel nozzle having its delivery end below the most constricted part of the venturi, a tube surrounding said nozzle in close proximity thereto carry air around and beyond the nozzle before delivery of the fuel to the venturi, means to feed fuel to the nozzle and air to said tube, a second fuel nozzle in the path of the main air supply of the carburetor, and a throttle valve surrounding the end portion of the air tube and pivotally mounted with relation thereto.

15 11. In a carburetor having a venturi, a fuel nozzle having its delivery end below the most constricted part of the venturi, a tube surrounding said nozzle in close proximity thereto to carry air around and beyond the nozzle before delivery 20 of the fuel to the venturi, a throttle valve surrounding the end portion of the air tube and slidably mounted with relation to the fuel nozzle, means to feed fuel to the nozzle and air to said tube, and a second fuel nozzle in the path of the main air supply of the carburetor.
